[57] CLAIM

The ornamental design for a wall or floor-mounted holder for a dispenser-equipped water cooler or the like, as shown and described.

DESCRIPTION

FIG. 1 is a perspective view of a wall or floor mounted holder for a dispenser-equipped water cooler or the like showing my new design, the broken-line showing of the water cooler being for illustrative purposes only and forming no part of the claimed design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and

FIG. 7 is a bottom plan view thereof.

FIG. 1
